UNITED STATES PATENT OFFICE.

ARNOLD STERN, OF HOLLIS, NEW YORK.

EMBROIDERY-MOUNT.

1,301,758.

Specification of Letters Patent. Patented Apr. 22, 1919.

Application filed February 15, 1918. Serial No. 217,854.

To all whom it may concern:

Be it known that I, ARNOLD STERN, a citizen of the United States, and resident of Hollis, in the county of Queens and State 5 of New York, have invented certain new and useful Improvements in Embroidery-Mounts, of which the following is a specification.

This invention relates to embroidery emblems, like initial letters, monograms, etc., such as are applied to articles of wearing apparel, house linen and the like, to serve as distinguishing marks thereon, and for ornamentation, and my improvement comprises 10 means whereby embroidery devices of this character may be provided with a form maintaining and supporting structure which will not obscure the color or pattern of or borne by the garment or article upon which 15 the emblem is to be mounted.

The practice in vogue for the application of manufactured embroidery emblems upon linen and other washable garments and articles has consisted in the employment of a 20 patch of opaque material having embroidered thereon an initial and an inclosing circle. These patches are unsightly and clearly indicate that the embroidered emblem is a manufactured article, not hand worked upon 25 the goods. Hence it is the purpose of my invention to employ as the base for the embroidery a material which, while permanently serving to maintain the form of the emblem, is transparent or translucent, and 30 therefore will not hide or obscure the pattern and color of the goods upon which said base is mounted in the application thereto of the emblem as a distinguishing mark.

In the drawing:

40 Figure 1 is a perspective view of a portion of a shirt sleeve having applied thereto one of my improved embroidered emblems. Fig. 2 is a section on the line 2—2 of Fig. 1, and

45 Fig. 3 is an enlarged plan view of the device.

In the example of my invention illustrated herewith, I have shown it as comprising a permanent base or mount 1 composed of a 50 diaphanous material, like silk chiffon, gauze, or other open work fabric, through which the

light may penetrate, so that when said base is applied in superposed relation with figured or colored goods, the latter may not be obscured thereby, but instead will be exposed to view through the meshes of said open work fabric. The said base 1 bears embroidered thereon an emblem or design 2, here indicated in the example as the initial letter S, and the base is surrounded by an 60 embroidery border 3, which both stiffens said base and binds its edge against disintegration.

The base is attached to the goods, as the shirt sleeve 4, as by stitching the border 3 65 thereto, for which purpose thread of the same color as the border is employed, and, by a process of overstitching, as at 5, not only will the attaching stitches be indistinguishable from the embroidered border, but 70 thereby the depth of embroidery of said border may be increased at will.

I claim:

1. An embroidery patch consisting of a permanent, form maintaining base of diaphanous material, for non-obscuring superposition upon a textile article, said base bearing an embroidered emblem, and an edge binding embroidered border for said patch.

2. An embroidery patch consisting of a permanent, form maintaining base of diaphanous material, for non-obscuring superposition upon a textile article, said base having a symmetrical outline bounded by an edge binding embroidered border, and an embroidered emblem worked centrally upon said base.

3. The combination, with a patterned textile article, of a distinguishing patch sewn thereto, said patch comprising a base of diaphanous material, through which the pattern of the article is visible, the outline of said base being bounded by an edge binding embroidered border, and an embroidered emblem worked upon said base.

Signed at borough of Manhattan, in the city, county and State of New York, this 7th day of February, A. D. 1917.

ARNOLD STERN.
